UNITED STATES PATENT OFFICE.

ISAAK MOELLER AND REUBEN ARKWRIGHT, OF NEW GLASGOW, NOVA SCOTIA,
CANADA, ASSIGNEES TO STERLING H. CAMPBELL, OF ST. LOUIS, MISSOURI.

UNCOUPLING DEVICE.

Application filed June 1, 1920. Serial No. 385,780.

To all whom it may concern:

Be it known that we, ISAAK MOELLER and REUBEN ARKWRIGHT, subjects of the King of Great Britain, and residents of the city of 5 New Glasgow, in the Province of Nova Scotia, Dominion of Canada, have invented certain new and useful Improvements in Uncoupling Devices, of which the following is a specification.

10 This invention relates to improvements in uncoupling devices, and the objects of the invention are to provide a simple and effective form of connection between the crank arm of the operating rod and the coupling 15 pin and further to provide such a form of supporting bracket for the operating rod as will enable it to be readily attached and detached.

Further objects of the invention are generally to improve and simplify the construction of the various parts to better adapt them to perform the functions required of them.

It consists essentially of the improved construction, particularly described, and set forth in the following specification and accompanying drawings forming part of the same.

In the drawings:—

30 Figure 1 is a view of an end of the freight car having our invention applied thereto.

Figure 2 is a side view of the same.

Figure 3 is a detail front elevation of the supporting bracket.

35 Figure 4 is a detail side elevation of the supporting bracket.

Figure 5 is a detail in plan of the arm on the operating rod.

Figure 6 is a detail sectional elevation of 40 the connecting link between the crank arm and the coupling pin.

In the drawings, like characters of reference indicate corresponding parts in all the figures.

45 Referring to the drawings, A represents a freight car of any suitable standard design. B indicates an operating rod for the uncoupling device having one offset end 10 adapted to constitute a hand operating lever, and another offset end 11 forming the crank arm by which the pin is lifted. The arm 11 is formed at the end with an eye 12 adapted to fit around the connecting link 13, which

is formed with turned ends 14 and 15, which extend laterally and prevent the eye sliding off the link.

By reference to Figures 5 and 6, it will be seen that the link 13 is formed from a single metallic rod bent to form an elongated eye 16 at the lower extremity which fits through 60 a perforation 17 in the coupling pin 18, the offset ends of the rod being brought together to form a central shank 19, and then being bent outwardly to form a T-shaped end constituting the hook shaped extremities 14 65 and 15.

The operating rod B is held in position by a bracket 20, on the side, and by a bracket 21 at the centre. The bracket 21 at the centre is of special design, being formed with a 70 side plate 22, a bottom plate 23 and an inclined mouth or socket 24 adapted to receive the rod B, and in which it is adapted to be retained by a suitable cotter pin 25.

Owing to the angular disposition of the 75 mouth 24 it is possible to readily remove and insert the operating rod. In inserting the link, it is first drawn up vertically, and the end is then connected to the link and then slid backwardly into the socket 24 in 80 the bracket, and located therein with a cotter pin, afterwards the side bracket 20 is attached to suitable holes.

As many changes could be made in the above construction, and many apparently 85 widely different embodiments of our invention, within the scope of the claims, constructed without departing from the spirit or scope thereof, it is intended that all matter contained in the accompanying specification and drawings, shall be interpreted as 90 illustrative and not in a limiting sense.

What we claim as our invention is:

1. In a car coupling device, a connecting link formed from a single piece of metal 95 bent upon itself to form an eye at one end and having a shank formed by two parallel abutting portions of the metal the ends of which are bent laterally in the plane of the eye at the outer end, as and for the purpose 100 specified.

2. In an uncoupling device, the combination with a coupler locking pin having an eye at its upper end, and an uncoupling lever having its inner extremity formed into a 105 vertically extending eye, of a rigid link hav-

ing substantially parallel arms, said link having an elongated loop formed at one extremity engaging the coupler locking pin eye, said parallel arms passing through said uncoupling lever eye and having their extremities turned outwardly in the plane of the link body to limit movement of the link through the said eye in one direction.

In witness whereof we have hereunto set our hands in the presence of two witnesses. 10

ISAAK MOELLER.
REUBEN ARKWRIGHT.
